SERIES SOCKET WITH RENEWABLE ELEMENTS

Reuben B. Benjamin, Chicago, Ill., assignor to
Benjamin Electric Manufacturing Company,
Des Plaines, Ill., a corporation of Illinois

Application April 14, 1930, Serial No. 443,937

5 Claims. (Cl. 173—344)

This invention relates to electric light sockets and has special reference to electric light sockets having removable elements. More particularly this invention relates to an electric light socket 5 having a base comprising a plurality of sections with the wiring terminals on one section and the side and center contacts attached to one of the other sections and electrically connected to the wiring terminals. Contact blades 10 are secured to both the side and center sockets which, when the socket is assembled, engage contacts carried in the outer section with the wiring terminals and connected therewith.

An object of this invention is to provide a 15 socket comprising a plurality of sections with the wiring terminals attached to an outer section and one of the other sections carrying the lamp contacts so that they may be removed and replaced in the event the contacts attached thereto become damaged by arcing, or from any 20 other cause, without the necessity of disconnecting the lead wires from the wiring terminals.

Where several lamps are connected in series 25 in a circuit, such as a 600 volt circuit, the lamp contacts of the socket are frequently damaged due to an arc being formed between the socket contacts and the lamp contacts, particularly between the center contacts. In the ordinary 30 socket when such damage occurs, it is necessary to disconnect the wires from the wiring terminal before dismantling the socket and replacing the damaged parts. With any socket embodying the present invention, if a contact becomes damaged, it is only necessary to 35 replace the section of the socket carrying the contact with a new section without disconnecting the wiring terminals from the wires, or removing the socket from the fixture supporting member to which it is attached.

The sections of the present socket are held 40 in an assembled position by two screws so that to replace a section it is only necessary to remove the two screws, replace the damaged section with a new one, and replace and tighten the screws—all of which may be done while the lead wires are connected to the wiring terminals of the socket. Thus, the more frequently 45 damaged and least expensive parts may be easily and inexpensively replaced.

A further object of the present invention is 50 to provide a socket in which the possibility of arcing is reduced to a minimum and any arcing that might occur is confined to the lamp cavity. The wiring terminals to which the lead

wires are connected are so far removed and protected from the lamp contacts that there is no possibility of the wiring terminals or lead wires connected thereto being burned or damaged by arcing between the lamp and socket contacts. 5 In order to prevent arcing between the conductors connecting the contacts to the wiring terminals, the conductors are extended through separate openings in the intermediate base section of the socket. Thus the possibility of any 10 arcing is confined to the lamp cavity where the arc will affect only parts that may be easily removed. To reduce the arcing in the lamp cavity between the side and center contacts the center contact is widely spaced from the shell. 15

A still further object of the present invention is to provide a socket in which the wiring terminals are protected from the heat caused by the lamp in the socket. The intermediate base section which separates the wiring terminals from the lamp cavity is made of heat insulating material, and there is very little air circulation to carry heat to the wiring terminals by convection of the air. Furthermore the distance between the contacts and the wiring terminals allows much of the heat that would be carried to the wiring terminals to dissipate. 20 25

Further objects and advantages of this invention will be more readily apparent from the following detailed description together with the accompanying drawings, in which latter:

Fig. 1 is a side elevational view, partly in section of the assembled socket and the securing screws;

Fig. 2 is a top plan view of the upper section 35 of the socket;

Fig. 3 is a vertical cross-sectional view taken on the line 3—3 of Fig. 2, and showing the center contact and sections connecting the center contact to a wiring terminal;

Fig. 4 is a vertical cross-sectional view taken on the line 4—4 of Fig. 2 and showing the side contact and connections connecting the side contact to a wiring terminal;

Fig. 5 is a top plan view of the middle section of the socket, showing the side and center contacts and the contact blades attached thereto;

Fig. 6 is a cross-sectional view of a wiring terminal and a contact connected thereto with 50 a contact blade engaging the contact;

Fig. 7 is a perspective view of the shell contact and flange and a contact blade;

Fig. 8 is a bottom plan view taken on the line 8—8 of Fig. 1 and showing the wiring terminals, 55

terminal plates and the spring contacts; and

Fig. 9 is a bottom plan view of the middle section of the socket taken on the line 9—9 of Fig. 1.

5 Referring more particularly to the drawings, the present construction comprises a socket 1 having a top section or base 2, a middle section or base 3 and a bottom section or base 4, each made of insulating material. The top section 10 2 is provided with an annular flange 5 which fits into the annular groove 6 formed in the top of the middle section, and the middle section 3 is likewise provided with an annular flange 7 which fits into the annular groove 8 provided 15 in the top of the bottom section 4.

Referring particularly to Figs. 2 and 6, the top section 2 carries the wiring terminals and a spring contact connected to each of the wiring terminals. Terminal screws 9 are threaded 20 into terminal plates 10 which are held in recesses in the bottom side of the top section 2 by means of screws 1a which are inserted through the top of the top section 2 and threaded 25 into threaded openings provided therefor in the terminal plates 10. Spring contacts 11 are likewise carried in recesses provided in the bottom of the upper section 2 and are held in place also by the screws 1a which pass therethrough before being threaded into the threaded 30 openings of the terminal plates 10.

The spring contacts 11 are of the type such as are used in the ordinary knife switch. The lead wires for connection with the terminal screws 9 are inserted from the top of the top section 2, 35 through holes 12 therein which are formed at each end of the groove 13, and then connected to the wiring terminals by the terminal screws 9.

The middle section 3 of the socket is preferably made of heat insulating material such as 40 procelain, although any other suitable material may be used, so as to prevent the heat in the lamp cavity from affecting the wiring terminals. This section carries the side and center contacts and the contact blades attached thereto for 45 electrically connecting the side and center contacts with the wiring terminals, as shown in Figs. 3 and 4. The shell contact 14 is crimped to a shell flange 15 for securing the shell contact 14 to the middle section 3. A contact blade 50 16, extending substantially straight upward, is attached to the shell flange 15, being preferably formed integrally therewith. The shell flange 15 is eyeleted to the middle section 3 of the socket by means of eyelets 17 so that the contact blade 16 will engage one of the spring contacts 11. The center contact 18 is attached at 55 one end to the top of the middle section 3 and then is bent down through an opening provided in the middle section 3 into the recess provided in the bottom of the middle section 3 so as to form a resilient contact.

A right-angled contact blade 19 is provided with a threaded opening adjacent one end. A screw 20 is extended through an opening provided therefor in the middle section 3 and passes up through a hole in the upper end of the center contact 18 and then threads into the threaded opening provided in the contact blade 19, thereby securing the center contact 18 and the contact blade 19 to the middle section 3. When thus secured, the upper end of the contact blade 19 is adapted to engage the other spring contact 11 when the socket is assembled.

The bottom section 4 of the socket is in the 75 nature of a ring having an opening in the center

thereof, through which the shell contact 14, attached to the middle section 3, extends. Various types of bottom sections or bases may be used with the same upper sections or bases, depending upon the purpose for which the socket is to be employed and the size of lamp to be used. The three sections, 2, 3 and 4, of the socket are held together by means of screws 21 which are inserted from the bottom of section 4 and extend up through the middle section 3 10 and thread into threaded members 22 which are permanently secured to the top section 2. With the above described construction, if either the side or center contact is damaged, it may be easily replaced by removing the screws 21 and 15 then replacing the middle section, after which the screws 21 are reinserted. All of this may be done without disconnecting the wires from the wiring terminals or without removing the top section 2, in which the wiring terminals are 20 placed, from the fixture supporting means to which it is attached.

In the claims where I have used the expression "quick detachable contacts", it is to be understood as defining a contact having a quick 25 detachable engagement and disengagement with respect to its cooperating contact blade.

While I have shown and described but one embodiment of the present invention, it will be apparent to those skilled in the art that 30 it may be embodied in still other forms without departing from the spirit and scope of this invention, and I desire, therefore, that this invention be limited only by the prior art and the 35 scope of the appended claims.

I claim:

1. A high voltage series socket construction comprising a three-part insulating base including upper, intermediate and lower coaxial cylindrical portions, anchorage nuts, two wiring terminals and two blade-engaging contacts all mounted on the upper base portion, said wiring terminals being accessible for wiring from the lower side of said base portion, a shell contact, a center contact and two contact-engaging 40 blades all mounted on the intermediate base portion, the lower base portion having a central recess to receive the shell contact, and screws spaced about the shell contact and extending through the lower base portion and intermediate 50 base portion and threaded into said anchorage nuts for securing the lower base portion and the intermediate base portion and the parts carried thereby to the upper base portion, said screws being accessible for operation from the lower 55 side of the lower base portion and said center contact and its corresponding blade having juxtaposed base portions and a screw extending through said intermediate base portion and the base portion of the center contact and threaded 60 into the base portion of the blade.

2. A high voltage series socket construction comprising a wiring base and contact member, a pair of wiring terminals mounted thereon, a pair of quick detachable contacts also mounted 65 thereon in electrical connection with said wiring terminals, respectively, said wiring base having a pair of recesses therein for said contacts, respectively, an insulating cover member extending across said recesses, a center contact mounted on said cover member, a contact blade mounted on said cover member electrically connected with said center contact and engageable 70 with one of said quick detachable contacts, an annular shell contact, and a blade electrically 75

- connected with said shell contact and extending through an opening in said cover member into engagement with the other of said quick detachable contacts, the electrical connection 5 between the blade and the shell contact lying substantially outside the cylindrical surface of the annular shell contact, said shell contact and associated blade being mounted on said cover member.
- 10 3. A high voltage series socket construction comprising a wiring base and contact member, a pair of wiring terminals mounted thereon, a pair of quick detachable contacts also mounted thereon in electrical connection with said wiring terminals, respectively, said wiring base having a pair of recesses therein for said contacts, respectively, an insulating cover member extending across said recesses, a center contact mounted on said cover member, a contact blade 15 mounted on said cover member electrically connected with said center contact and engageable with one of said quick detachable contacts, an annular shell contact, a blade electrically connected with said shell contact and extending 20 through an opening in said cover member into engagement with the other of said quick detachable contacts, the electrical connection between the blade and the shell contact lying substantially outside the cylindrical surface of the 10 annular shell contact, said shell contact and associated blade being mounted on said cover member, an insulating sleeve surrounding said shell contact, and securing means extending through said sleeve and cover member and anchored to said wiring base.
- 15 5. A high voltage series socket construction comprising a wiring base and contact member, a pair of wiring terminals mounted thereon, a pair of quick detachable contacts also mounted 20 thereon in electrical connection with said wiring terminals, respectively, said wiring base having a pair of recesses therein for said contacts, respectively, an insulating cover member extending across said recesses, a center contact 25 mounted on said cover member, a contact blade mounted on said cover member electrically connected with said center contact and engageable with one of said quick detachable contacts, an annular shell contact, a blade electrically connected with said shell contact and extending 30 through an opening in said cover member into engagement with the other of said quick detachable contacts, the electrical connection between the blade and the shell contact lying substantially outside the cylindrical surface of the 35 annular shell contact, said shell contact and associated blade being mounted on said cover member, an insulating sleeve surrounding said shell contact, the connection between said shell contact and blade lying between the cover member and the insulating sleeve.
- 25 4. A high voltage series socket construction comprising a wiring base and contact member, a pair of wiring terminals mounted thereon, a pair of quick detachable contacts also mounted 40 thereon in electrical connection with said wiring terminals, respectively, said wiring base having a pair of recesses therein for said contacts, respectively, an insulating cover member extending across said recesses, a center contact mounted on said cover member, a contact blade

REUBEN B. BENJAMIN.
